UNITED STATES PATENT OFFICE

2,455,492

CIGARETTE HOLDER

William L. Jackson, Greenville, S. C.

Application February 23, 1945, Serial No. 579,411

2 Claims. (Cl. 131—175)

1

This invention relates to a cigarette holder which is capable of being used in places where smoking an unshielded cigarette is hazardous or where there is no ash tray for depositing the ash from the burning cigarette. It is especially adaptable for use by members of the armed services in places where a glow or a light might reveal the whereabouts of the smoker to the enemy. It is also very adaptable for use in factories, offices, warehouses, as a safety factor against the spreading of fires. The cigarette holder is especially adaptable for use with a chemical lighter such as shown in Patent Number 2,005,476 to Schmitt which can be inserted in the end of the cigarette holder and the cigarette lighted without a flash such as is the case where a match is struck for lighting a cigarette.

It is a well known fact that soldiers in the field and under fire or sailors on ship board, where they are exposed to view, would desire very much to smoke, but the same is not feasible for the reason that in striking a match to light a cigarette, there is a flash of light which reveals the whereabouts of the soldier or sailor to the enemy, and also even after the cigarette is lighted, the glow of the coals thereon also reveals the whereabouts of the smoker to the enemy.

There is on the market and in general use, a cigarette lighter which is commonly known as a chemical lighter, and in which there are certain chemicals which when a button is pressed on the lighter and the lighter is held to a cigarette, causes the cigarette to be lighted, yet if the cigarette lighter is held in open view and the button to the lighter is pressed, there will be no outside illumination, and it is with this type of lighter that my cigarette holder is especially adapted to be used, because with my cigarette holder and the chemical lighter, a soldier or sailor on duty if not forbidden could light a cigarette and smoke the same without any substantial amount of glow showing, because the cigarette would be lighted within the holder and when the lighter is withdrawn, a shutter is moved to a closed position. The cigarette holder comprises inner and outer members which are slotted in offset relation so as to allow ventilation within the lighter and yet prevent any substantial amount of glow from passing to the exterior of the holder.

It is therefore an object of this invention to provide a cigarette holder especially adaptable for use with a chemical lighter and which will enable a cigarette to be smoked in any place without danger of fire or a give-away glow either

2

in the act of lighting a cigarette or while smoking the same.

It is also an object of this invention to provide a cigarette holder which can be used by civilians without any danger of igniting other objects from the cigarette and which takes care of its own ash, as the ash from the burning cigarette remains within the cigarette holder and can be dumped from either end of the cigarette holder as desired.

Some of the objects of the invention having been stated, other objects will appear as the description proceeds, when taken in connection with the accompanying drawings, in which:

15 Figure 1 is an elevation of my improved cigarette holder;

Figure 2 is a longitudinal sectional view of Figure 1 and taken in a vertical plan in Figure 1;

Figure 3 is a view similar to Figure 1 but showing the most of the outer shell broken away;

Figure 4 is an end view looking at the right hand end of Figure 1;

Figure 5 is a cross sectional view along the line 5—5 in Figure 1;

Figure 6 is an end view of the left hand end of Figure 1 but showing the cover member removed;

Figure 7 is an elevation of the left hand end of Figure 1 showing the cover in position;

Figure 8 is a cross sectional view taken along the line 8—8 in Figure 1;

Figure 9 is an end view of the left hand end of Figure 1 showing the cover in open best position;

Figure 10 is a cross-sectional view taken along the line 10—10 in Figure 1.

35 Referring more specifically to the drawing the numeral 10 indicates a mouthpiece which has an enlarged annular portion 11 which is covered and reinforced by a metallic annular member or ferrule 12. This mouthpiece has a passageway 13 extending therethrough and through which the smoke from the cigarette is drawn into the mouth of the user. This mouthpiece 10 is adapted to have fitted into the left hand end thereof in Figures 1 and 2, a conventional cigarette 14. Adapted

40 to slidably contact the exterior of the mouthpiece 10 is the restricted annular portion 15 of an inner barrel 16. Inner barrel 16 has two, oppositely disposed slots 17 and 18 therein, through which the air 45 may pass to the interior of barrel 16. Barrel 16 is open at its left hand end in Figures 1, 2, and 3. Adapted to slide in slot 18 is a screw threaded member 19 having a head on its outer end which engages the exterior of the barrel 16, the shank 55 of screw 19 being embedded in annular portion

11 of the mouthpiece after penetrating the ferrule 12. This guides the mouthpiece 10 when it is slid relative to the barrel member 16 and prevents relative turning movement between the barrel 16 and the mouthpiece 10.

Integral with the barrel 16 is an outer barrel 21 which is spaced somewhat from the inner barrel 16 to provide a space 22 between the inner and outer barrels. The right hand end of barrel 21 and the right hand end of barrel 16 are fused together as the outer barrel has an end wall 23 extending inwardly from the outer barrel 21 and is fused to the annular portion 15 of the inner barrel. A pair of openings 24 and 25 are provided to allow air to enter in between the inner and outer barrels.

At the other end, or left hand end of the cigarette holder as shown in Figures 1, 2, and 3, the inner and outer barrels are made integral with each other, but as before stated, left hand end of barrel 16 is open and is adapted to be closed by a swinging shutter 26 having a pair of prongs 27 integral therewith which are pivoted as at 28 on each side of barrel 21 and which lid or cover can be raised or flung to one side as shown in Figure 9 to allow a cigarette to be inserted when the mouthpiece 10 is slid to the left in Figures 1, 2, and 3, and then when the parts are returned to the position shown in Figures 1, 2, and 3, the lighter can be inserted into the inner barrel to light the cigarette but of course, if it were to be used in civilian life, the cigarette could be lighted by an ordinary match while its left hand end is projecting from the open end of barrel 16.

The shutter 26 is adapted to be arrested in proper position by means of a projection 30 projecting from one or both sides of the outer barrel 21.

It is to be noted that the slots 17 and 18 are disposed at substantially 180 degrees apart from each other whereas the outer shell 21 has a pair of slots 31 and 32 which are disposed in the exterior shell 21 in offset relation to the slots 17 and 18 of inner barrel 16, so that any glow which might pass out through the inner slots would not be visible for any substantial distance through the outer slots 31 and 32 in the outer barrel 21.

In the drawings and specification, there has been set forth a preferred embodiment of the invention and although specific terms are employed, they are used in a generic and descriptive sense only and not for purposes of limitation, the scope of the invention being defined in the claims.

I claim:

1. A cigarette holder comprising a mouthpiece having a passageway therethrough, into one end of which one end of a cigarette is adapted to be placed, said mouthpiece having a peripheral shoulder on the end which receives the end of the cigarette, a shield member comprising an inner tubular member open at one end and having an inwardly projecting shoulder at its other end slidably mounted on the mouthpiece to prevent separation of the mouthpiece from the tubular member when the two parts are in extended position, said tubular member having joined to each end thereof, and in spaced relation thereto, by end walls, an outer member which is rectangular in cross section, the end wall adjacent the mouthpiece having openings therein, the side walls of the outer member having longitudinally

extending slots therein and the inner tubular member having longitudinal slots therein disposed substantially 180° apart and in non-registering position with the slots in the outer member, the peripheral shoulder on the mouthpiece having secured therein a screw which projects through one of the slots in the tubular member to guide the mouthpiece relative to the tubular member when the mouthpiece is telescoped within the tubular member, and a pivoted closure member mounted on the shield member for closing the open end of the tubular member.

2. A cigarette holder comprising a mouthpiece provided with a smoke passageway which is enlarged at its inner end for receiving one end of a cigarette, the inner end of the mouthpiece having a shoulder portion extending entirely there-around, a tubular member, open at one end and having an opening in the other end of less diameter than the inside diameter of the tubular member, to prevent the shoulder on the mouthpiece from passing out of the tubular member when the tubular member and the mouthpiece are in extended position, a shell member, rectangular in cross section, and surrounding said tubular member in spaced relation to the exterior of the tubular member and having its end remote from the mouthpiece cast integral with the end of the tubular member, a wall closing the end of the shell member adjacent the mouthpiece and having an opening therein for slidably receiving the mouthpiece and having additional openings therein to permit ventilation in the space between the shell member and the tubular member, the shell member having a longitudinally extending slot in one of its side walls near the bottom portion of said side wall and having a longitudinally extending slot in the opposite side wall near the top of said side wall, the inner tubular member having opposed longitudinally extending slots therein disposed at substantially 90° from the slots in the shell member, the mouthpiece having embedded in its end portion which is disposed inside of the tubular member a projection which extends through one of the slots in the tubular member to guide the mouthpiece relative to the tubular member when they are telescoped, and a closure member movably mounted on the shell member for closing the open end of the tubular member.
